UNITED STATES PATENT OFFICE.

GEORGE H. MILLER, OF BLOOMINGTON, ILLINOIS.

WATER-CLOSET FLUSHING APPARATUS.

SPECIFICATION forming part of Letters Patent No. 680,459, dated August 13, 1901.

Application filed March 26, 1900. Serial No. 10,304. (No model.)

To all whom it may concern:

Be it known that I, GEORGE H. MILLER, a citizen of the United States, residing at Bloomington, in the county of McLean and State of Illinois, have invented a new and useful Improvement in Flushing Water-Closets; and I do hereby declare that the following specification, taken in connection with the drawings furnished and forming a part of the same, is a clear, true, and complete description of my invention, which relates to a device for the direct flushing of water-closets, by which I attain an improved flushing effect over the ordinary elevated tank through the direct pressure of the main, by which the bowl of a water-closet is thoroughly flushed or cleaned.

The object of the invention is to provide an improved construction of apparatus for the above purpose which shall possess superior advantages with respect to efficiency in use.

My invention consists in the novel construction and combination of parts whereby is obtained an automatically-controlled direct flush to the bowl, as hereinafter fully described and claimed.

In the accompanying drawings, Figure 1 is a central longitudinal section of a small pressure-tank constructed in accordance with my invention, showing the parts of the interior construction. Fig. 2 is a vertical section of the same. Fig. 3 shows a portion of the tank through a horizontal section. Fig. 4 is an enlarged detail section of the release-valve. Figs. 5 and 6 are enlarged detail sections of the cylinder and admission-valve. Fig. 7 is a detailed horizontal section of the same. Fig. 8 is an elevation and part section of the stopper or flushing-valve with piston attached. Fig. 9 is an enlarged detail section of the connecting air-valve.

In the said drawings the reference-number 1 designates a small closed pressure-tank constructed in manner and consisting of two separate compartments 2 and 3, having a dividing partition separating the water-compartment from the chamber in which the compressed air is confined, the tank being of the capacity of about six hundred cubic inches and approximately rectangular or of any suitable shape and size. The tank is calculated to be placed directly above and just back of the closet-bowl or is adapted to

be secreted in the wall back of same and directly connected thereto. The lower or bottom side of the tank is formed with an opening 4, communicating and connected with the flush of the bowl, with a stopper 5, adapted to act as a release-valve for opening and closing said opening. Located in said tank is a vertical cylinder 6, situated over and above the flush-opening 4 and attached thereto and extending upward about one-half the height of the tank, with the upper end closed and provided with two slotted openings near the lower end 7. Located in said cylinder is a vertically-movable stopper 5, coinciding with the flush-opening 4, having a piston 8 attached to the upper end thereof, dividing the cylinder into two compartments 9 and 10.

The numeral 11 designates a valve-casing provided with port-openings 12 and 13, communicating, respectively, with the expanding chambers 9 and 10 above and below the piston. Located in said casing are two alternating supply-valves 14 and 15, connected to a pivoted rocking lever adapted to alternately open and close said ports, which communicate with the cylinder-compartments 9 and 10. Connected with said valve-casing is the main or direct supply-pipe 16. The admission of water under pressure from said main through the valve-port 12 serves to expand the compartment 9, thereby causing the piston 8 to rise, and with it the stopper 5, from the opening 4, and in like manner by admitting water through the port-opening 13 into the compartment 10 by means of closing valve 14 and opening valve 15 will cause the piston 8 to lower, and with it the stopper 5, acting as a valve for closing the opening 4 by the force of the direct pressure of the water from the main, the valves 14 and 15 being adapted to alternately open and close the ports 12 and 13 by means of a float 17, having the arm 18 pivoted to a bracket 19, connected to the valve-casing 11. The numeral 20 is an oscillating weight, with an arm 21 also pivoted to said bracket. This weighted arm is pivoted to a link 22, being pivotally connected with the crank 23, secured to the shaft, to which is attached the rocking lever of valves 14 and 15, the arm of the said weight being linked to the valves, and having lugs 24 and 25, corresponding and coinciding with the lugs in the arm of the float, said lugs

being adapted to come in contact and oscillate the weight by reason of the float elevating and lowering, causing the weight to be alternately carried over its center of gravity 5 and allowed to drop, operating the valves 14 and 15, and thereby affording quick action in opening and closing the admission-ports 12 and 13. The by-pass chambers 26 in the cylinder 6 are adapted to communicate between 10 the flush-opening 4 and the expanding compartment 9 and port 12 for the free passage of water direct from the main into the bowl during the process of flushing.

The valve-casing 27 of the release-valve 28 15 is connected with the pipe 29, attached to the upper end of the cylinder 6 and communicating with the upper compartment 10 of said cylinder, the pipe 30 being connected to said valve-casing and communicating with the 20 flush-opening 4. The shaft 31, attached to valve 28 and inclosed within the valve-casing 27, extends through the tank and with an eccentric attachment to the crank 32, hand-wheel, or other means for opening and operating the 25 valve 28.

Numeral 33 is a coiled spring attached to the shaft 31, being the means of making the valve 28 self-closing immediately after the crank 32 is released by the operator.

30 The float air-valve 34 is adapted as a means for communication between the water and compressed-air compartments 2 and 3, and said valve closes off by means of a float 35 within the casing 36. When the compartment 2 is 35 full of water, or nearly so, the water will enter the valve-casing 36 by the way of the tube 37 and raise the float 35, causing the valve 34 to close. When the compartment 2 is filled with water under the usual pressure of the 40 main, the displaced air from said compartment is forced into the air-compartment 3 and compressed until the valve 34 is closed. The relative size of the compartments 2 3 should be such that when the water-compartment 45 is filled by the variable pressure of the main, which may be from forty to eighty pounds, the air-pressure in the compartment 3 will exert a pressure of, say, twenty-three pounds. This relative pressure in the two 50 compartments may, however, be varied within certain limits without departing from the spirit of my invention. When the water from compartment 2 is released in flushing the bowl, the superior pressure of the air in compartment 3 unseats the valve 34 and forces the water out of cup 36. It is to be noted 55 that the valve 14 does not close tightly, and the opening is sufficient to merely check the flow of water from the main and to insure a 60 regulated ingress. The opening to tube 37 may be of any desired height, so as to admit of the air-space in upper part of compartment 2 to be varied in size for the purpose of creating a greater or less force to the 65 discharge of the water out of compartment 2 at the starting of the flush, this air-space being subjected to a compression in volume in

proportion to the pressure upon the main and therefore has a greater expanding force in proportion to its volume than the air contained in compartment 3, the object being to control the force required for different makes of closet-bowls under the varying pressures of the main.

The operation for flushing will now be as follows: Referring now to Fig. 1, the operator will start the flush by turning the crank 32, which by means of the shaft opens the valve 28, making a free communication between the flush-opening 4 and the compartment 10 of the cylinder 6, which act serves to release the pressure in said compartment and cause the lower compartment 9, the same being likewise under pressure from the direct main, to expand and raise the piston. Said piston being connected with the stopper 5 will cause the stopper to rise from the flush-opening 4. This completes the operation for starting the flush. The water of the main is now admitted from the port 12 under the direct pressure through the compartment 9 and by means of the by-pass chambers 26 discharging directly into the flush-opening 4 of the tank and into the bowl. The water in the tank being under the pressure of the air confined in the compressed-air compartment 3 will at the same time be forced out of the tank through the slotted openings 7, engaging with the water of the direct pressure and discharging therewith into the flush-opening, 100 and by this contact an ample, rapid, thorough, and uniform flush is attained. As the water is thus escaping from the tank the level thereof will of course fall and the float 17 will fall accordingly. As the float falls 105 the lug 24 of the arm carrying the float will engage with a coinciding lug in the arm of the oscillating weight 20, causing the weight to be carried over its center of gravity, whereby it is overbalanced and allowed by 110 its weight to drop. The arm of the weight being linked to the rocking lever of the valves 14 and 15 acts as a means of closing the port 12 and opening port 13. The water now entering the compartment 10 through said 115 port will cause same to expand, forcing down the piston 8 and with it the stopper 5, closing the flush-opening 4. The flush being now completed and the tank closed will again 120 refill with water through the port 12, which is adapted to be left slightly open for the admission of water for the refilling of the tank through the slotted openings 7. While the tank is thus slowly refilling the air contained in said tank will be forced into the air-compartment 3, through the valve 34, communicating between the two compartments. As 125 soon as the water reaches a point near the top of said compartment on a level with the open upper end of tube 37, said tube communicating with the bottom of the float air-valve casing 36, water will be admitted 130 through the tube into the valve-casing, causing the float 35 to elevate and closing the

valve 34. Said float being suitably constructed of a light material the confined air within the compressed-air chamber 3 will be under a pressure in proportion to the size of 5 said air-compartment to the total capacity of the tank. The air-compartment being separated from the water-compartment of the tank, the valve communicating the same is adapted to regulate and maintain a given 10 and uniform pressure, which is applied as a medium of force for expelling the water out of the tank and into the flush-opening, insuring at all times a regular, even, and uniform flush irrespective of the varying and irregular pressures to which the source of 15 water-supply from the main may be subjected.

Having thus fully described my invention, what I claim is—

1. In a water-closet flushing mechanism, 20 the combination with the flush-tank formed with a flush-opening and the plug for opening and closing said opening, of the cylinder located in said tank above and coincident with the flush-opening and connected directly with the main and the piston located in said cylinder for raising said plug and admitting water under direct pressure from the main into said cylinder from whence it will escape and engage or come in contact with 25 the water of the tank in proximity to said opening and be discharged therewith through said opening.

2. A flushing apparatus comprising a tank with water-compartment normally in direct 30 communication with the water-supply main, the flush-opening formed with an internal cylinder located directly over and attached to said opening, the upper end of the cylinder closed having slotted openings near the lower 35 end for the escape of water from the tank into the flush-opening, the by-pass chambers on opposite sides through which the water from the main is discharged into the flush-opening of said tank, the vertically-movable stopper 40 or valve coinciding with the said flush-opening located within said cylinder, the piston secured to the upper end thereof dividing the cylinder into expanding compartments, of 45 means for alternately admitting water from the main into the expanding compartments of said cylinder to open and close the flush-opening and the water from the main discharging together with the water of the tank through the flush-opening, substantially as 50 described.

3. A flushing apparatus comprising a pressure-tank with water-compartment normally in direct communication with the water-main, and a separate air-compartment, the means 55 for separating the said compartments by an air-valve connecting said water and air compartments, a tube and a float in said air-valve adapted to close the communication between the said compartments by the rise of water in the water-compartment and entering said tube, raising the float and closing the valve and to be opened by reason of the superior pressure in

the water-compartment 2 being released during the flushing operation, the flush-opening and expanding cylinder with plug and pistons for discharging water from tank and main directly into and through the flush-opening, substantially as described. 70

4. A direct-pressure flushing mechanism comprising a water-tank with separated air-compartments, the water-compartment normally in direct connection with the water-supply, the air-valve connecting said compartments with float and inlet-tube to said valve, to control the expanding force to the 80 water discharging from the tank at the start of the flushing operation, and means for releasing the pressure and discharging the water from the main and water-compartment into the flush-opening, and unseating the air-valve between said compartments by reason of the greater pressure in the air-compartment 85 3 forcing open the said valve, substantially as described.

5. The combination of the direct-pressure 90 and flush tank, for flushing water-closets, formed with separate compartments, with the float air-valve between said compartments, and flush-opening, the cylinder located in said tank closed at the upper end, with 95 slotted openings near the lower end, the bypass chambers on opposite sides of said cylinder, the piston and stopper within said cylinder forming expanding compartments, the oscillating weight and float-ball, the alternating valves connected to said weight and ball for operating said valve to admit water alternately from the main into the cylinder-compartments expanding the piston for elevating and automatically lowering the stopper, opening and closing the flush-openings, of means for starting the flush and releasing the pressure on the piston in the upper cylinder-compartment to raise the stopper and opening the flushing-valve, substantially as described. 100 110

6. In a flushing-tank mechanism for flushing water-closets, by direct pressure of the main, of the character described, with separate compartments and float air-valve between them, the cylinder and stopper with piston in 115 the expanding compartments, means to admit water from the main, a cylinder-valve, the bypass chambers on opposite sides of said valve through which the water of the main is discharged with the water of the tank into the 120 flush-opening in said tank, the alternating valves with oscillating weight and float, the self-closing release-valve and pipe from same to upper end of cylinder and waste-pipe attached connecting the upper expanding compartment of cylinder with flush-openings, of 125 means for operating said valve to start the flush, substantially as set forth.

7. In a direct-flushing mechanism for the flushing of water-closets, the combination of 130 the tank of separate compartments formed with a flush-opening and cylinder attached to said opening having slotted openings at the lower end and closed at the upper end, and

by-pass chambers on opposite sides of said cylinder through which the water is directly discharged from the main supply-pipe into the flush-opening with the water in said tank,
5 the alternating valves attached to cylinder with oscillatory weight and float-ball adapted to alternately admit the water from the main to the expanding compartments of the cylinder, expanding the piston and causing the
10 stopper to rise and fall opening and closing the flush-opening, the self-closing release-valve with release and waste pipe attached, the shaft with crank or hand wheel opening the release-

valve releasing the pressure in upper expanding compartment of the cylinder, elevating 15 the stopper and starting the operation of flushing the closet-bowl, the floated air-valve and casing communicating between the water and air compartments of the tank, substantially as set forth and described.
